UNITED STATES PATENT OFFICE.

EDMUND WEIDNER, OF BERLIN, GERMANY.

APPARATUS FOR THE DELIVERING OF SOAP AND THE LIKE IN PORTIONS.

Application filed April 22, 1926, Serial No. 103,885, and in Germany November 6, 1925.

For storing and delivering creams, pastes and the like, for instance tooth-paste, tubes of lead or tin have hitherto been used. The lead tubes are very disadvantageous owing 5 to the poisonousness of the lead which frequently causes eczema and other diseases. The tin tubes are comparatively expensive so that by the use of such tin tubes the sale price for the pastes and cream is considerably increased.

By the present invention a very practical, simple and cheap packing and delivering device for consistent pastes, creams, soaps and the like is created, which is free of the above 15 mentioned inconveniences, and ensures at the same time a very economical delivery of the paste, soap or the like in the most comfortable form.

The invention consists essentially in that 20 on one of the ends of a packing sleeve of convenient material as cardboard or the like, a cutting edge is movably arranged in such a manner that by means of this cutting edge a thin slice can be cut off the mass which is 25 permanently pressed towards said cutting edge. With this object in view it is merely necessary, that the paste, cream or the like be of sufficient consistency to be cut into thin slices, as is always the case with solid soap.

30 Preferably the cutting edge is formed by a plane-iron which can be moved in straight line or along an arc of a circle and in such a manner that a slice is cut off the mass only if the cutting-edge moves in the one 35 direction. The adjusting of the mass towards the delivering end of the sleeve may be effected by hand or mechanically, e. g. by means of a spring.

This device according to the invention 40 may further be developed by utilizing the apparatus for delivering soap in portions preferably as a penny-in-the-slot device. Either the knife or plane or the block of soap can execute the movement for the step- 45 wise cutting off of soap portions, and this movement may be made possible by the insertion of a coin. Whereas single thin plates of soap packed and stored separately will dry strongly during storage and lose their 50 smell, the user of the apparatus according to the present invention always will receive freshly cut slices of soap.

55 Preferably the arrangement is such, that the knife, plane or the like, or the block of soap are moved in an arc of circle by means of a rotatable arm, and said arm may be

coupled by an inserted coin which drops into a slot of said arm, with a handle having a corresponding slot and being freely rotatable around the same axle as said arm.

With this apparatus a device for delivering a piece of paper or fabric may be combined in a simple and practical manner, said sheet of paper or fabric being designed to serve as a towel or for any other purpose. The conveying rolls for the paper or fabric may be rotated from the arm coupled with the handle by the inserted coin. Further objects of the invention will be stated in the following detailed description, 70 illustrated in the drawings, and in the annexed claims.

Embodiments of the invention are shown as examples in the accompanying drawings in which:—

Fig. 1 shows in front elevation the improved packing with the delivering means;

Fig. 2 is a side elevation of Fig. 1, one of the long walls of the packing being partly broken away;

Fig. 3 is a plan view of Fig. 1;

Fig. 4 shows in front elevation the packing when in use, the slide being pulled out;

Fig. 5 is a perspective view showing one form of construction of the slide on a larger 85 scale;

Fig. 6 is a similar view showing a modified construction of the slide;

Fig. 7 is a front elevation of the automatic device, partly in section;

Fig. 8 a side elevation of Fig. 7;

Fig. 9 shows the lower part of this apparatus in longitudinal section, viewed from the front; and

Fig. 10 is a plan view of the same apparatus, the cover-plate being removed.

In the embodiment shown in Figs. 1 to 6 the mass *a* is stored in a sleeve *b* of cardboard or of other material for instance sheet metal. This sleeve *b* is open at both ends. 100 On the one end of the sleeve, through which the mass is inserted, a plate *c* is arranged for closing the sleeve and for covering the corresponding end of the block *a* of the mass, this plate being movable in the sleeve *b*. 105 The plate *c* may be stuck onto the block *a* either by a special adhesive substance or by the natural sticking capability of the mass used (for instance paste or cream). At the lower end of the open sleeve *b* flanges or 110 abutments might be provided in order to prevent the plate slipping out of the sleeve *b* together with the mass.

In one long side or in two opposite long sides of the sleeve *b* slots *d* are arranged which are of such width that the user can insert his finger and press upon the plate *c*. These longitudinal slots are closed by, preferably transparent, paper so that through this paper *e* the mass in the sleeve can be observed. The paper has preferably a line of perforations *f* in longitudinal direction or it might have some transverse lines of perforation spaced at convenient distances so that pieces of the paper may be torn off according to the length of the block *a* which will yet be present.

The delivering device is mounted on the end of the sleeve *b* opposite to the end through which the mass is inserted. The delivering device consists for instance of a frame *g* of sheet metal fixed if necessary on the sleeve *b* by rivets or other convenient means. The upper ends of the longitudinal edges of the frame *g* are flanged twice to form guides *h*. In these guides *h* a slide *i* of sheet metal is guided. This slide *i* has at one end tongues *k* which are stamped out of the slide and are bent in outward direction to serve as stops and bear against flaps *l* at the inner ends of the guides *h* if the slide is pulled out into the position shown in Fig. 4, the movement of the slide in this direction being thus limited. Near the end of the slide *i* where the tongues *k* are arranged a flap *m* is stamped out of the slide and bent inwardly. This flap *m* forms a plane-iron, the front edge of said flap *m* being sharpened if necessary. In a small distance behind this flap *m* a window *n* is cut out of the slide *i*, as shown in Figs. 1-5, the flap *o* of material which is thus obtained being bent outwards over the knife *f* to serve as abutment for the slice of paste or the like which is being severed from the block *a* so that this slice is pushed away from the sleeve when the slide *i* is being pushed back. The window *n* is preferably closed by a pane of transparent material, e. g. a film, gelatine or the like. The rear end of the slide may be curved upward or downward after the slide has been inserted into the guides so that it can serve as a handle and to limit the movement of the slide.

To use the device, a pressure is exerted by a finger from the outer side upon the plate *c* so that the mass *a* is pressed against the slide *i*, whereupon this slide is pulled out from the position shown in Fig. 1 into the position shown in Fig. 4. During this movement the knife *m* cuts a thin layer or slice *q* from the mass *a* (Fig. 4), and this cut off slice of mass passes to the outside through the interval between the cutting edge of the knife and the slide *i* and rests upon the slide and upon the free surface of the mass *a* respectively. If the slide *i* is pushed in again, the slice *q* of mass *a* is pushed in front of the

flap *o* for instance onto a tooth brush or a hand, or the like held beside. The mass *a* then again is completely covered by the slide *i*, and the device is again ready for use. In accordance with the diminishing length of the block *a* in sleeve *b* (Fig. 4) the transparent paper *e* which covers the slots *d* can be torn off to facilitate the access to plate *c*.

The knife *m* of the slide *i* shown in Fig. 6 is constructed in such a manner that its side edges are still attached to the slide *i*. Instead of the flap *o* which has been cut out of the material of the slide in the production of the window *n* according to the form of construction shown in Fig. 5, the front edge of the slide *i* according to that shown in Fig. 6, is slightly bent outward at *p* so that it serves as an abutment for the cut off slice which thus is pushed off the block when the slide is being pushed in.

The construction of the slide and of the cutting device on the same may also be modified in other directions, for instance the cutting device may be formed by a thin wire stretched in convenient manner and adapted to act as cutting edge. The guide frame for the slide may be made in one piece with the packing-sleeve if this sleeve is made of sheet metal. The knife, instead of being movable in longitudinal direction, may be rotatable or shiftable along an arc of a circle so that a slice is cut off and delivered if said cutting device is rotated. Instead of pressing the mass onto the knife by a pressure of the finger this may be effected mechanically by weight or by a spring.

In the embodiment shown in Figs. 8 to 10 a feed- and driving wheel 1 is clamped on the lower threaded end of a vertical shaft 7 between two collars 2 and 3 fixed by means of a nut 10. The feed- and driving wheel 1 consists preferably of a metal rim with spokes or a connecting plate not shown in the drawings. Into the circumference of the sheet-metal rim teeth are cut near the upper edge, whereas incisions are arranged near the lower edge of said rim in regular distances from one another. A ratchet pawl 14 is provided to engage with said incisions of said rim. Above the feed wheel 1 the knife 42 is clamped in shaft 7. At the right and left of shaft 7 tubular sheet-metal sleeves 4 of oval cross section are arranged, which contain each a soap stick 31. A pressure-piece 8 having two laterally projecting arms 120 is mounted on shaft 7 so that it rests upon the upper surface of the soap-sticks 31. At the center of this pressure piece 8 an internally threaded hole is arranged, and the piece 8 is screwed on the worm part 17 of the vertical shaft 7. A spring 9 loosely arranged on shaft 7 presses in the beginning of the work from above upon said pressure-piece 8 and serves for ensuring at the beginning of the operation the engagement be- 130

tween the pressure piece 8 and the worm 17 of shaft 7. A spring 9' is mounted on the lower end of shaft 7 and, acting from below upon said pressure piece 8 if the soap block has been consumed, serves to keep the pressure piece 8 away from the knife 42. The sleeves 4 are closed at the top end by a lid 5 hingedly fixed by a hinge 6 on the rear wall 34 of the casing of the apparatus. The upper end of spring 9 bears from below against said lid in the beginning of the work.

On the lower end of shaft 7 two arms 13 and 20 are loosely mounted above a nut 12, said arms having each a coin-slot. The upper arm 13 carries further a ratchet pawl 14, pivotally mounted at 16, controlled by a spring 15 and adapted to engage with the incisions in the lower part of the rim of feed wheel 1 (Figs. 9 and 10). The lower arm 20 projects through a slot in the wall 33 of the casing and serves as handle for operating the apparatus. A spiral spring 19 arranged underneath said arm 20 tends to permanently return this arm to the starting position.

If the arms 13 and 20 are in their normal position of rest, the coin-slots in the same register with a coin-slot in a horizontal partition 48 under which an inclined coin-channel 40 is arranged. The slot in the horizontal partition 48 is of such dimension that inserted coins which are of less diameter than required, will drop through the slots in the arms 13, 20 and through that in the partition 48 into the coin-channel 40. The partition 48 has on an opposite point a larger slot 43 through which the correct coins may drop into a cash drawer 38. This cash drawer is inserted from below into the open end of the casing 33. The cash drawer is open at the top end and has a transverse bar 44 near its upper end under which grips the bent end 45 of a vertical rod 46, the upper end of which is fixed by means of a thumb nut 47 to a convenient holder fixed to the casing 33.

A toothed wheel 21 gears with the teeth in the upper part of the rim of feed wheel 1, and smaller gear wheels 22^a, 22^b gear with said toothed wheel, said small gear wheels being keyed on vertical shafts 25. On these shafts 25 rubber rolls 24 are fixed which are in contact with one another and pressed strongly together by the action of pull springs 26. On a partition 25 arranged above the toothed wheels a bobbin 29 is rotatably mounted by means of ball bearings 41, a roll 30 of paper or fabric being mounted on said roll. The end of the paper strip wound onto the bobbin passes through between the rubber rolls 24 and through a vertical slot 49 in the wall 33 of the casing (Fig. 10).

An eccentric lever 27 is connected with the toothed wheel 21 and operates a counter 28,

which indicates how many portions of soap have been delivered.

The casing 33 is closed by a cover plate 32 which has at the rear end a vertical flange adapted to be inserted from below under a corresponding flange of the rear wall 34 of the casing, whereupon the cover plate can be locked on the casing 33 by means of a lock. The cover plate 32 covers also the thumb nut 47 so that the cash drawer 38 cannot be removed before the cover plate 32 has been unlocked and opened. The rear wall 34 is fixed on a chamber wall or the like by means of stone-bolts 35 and nuts 36.

The operation of the apparatus is as follows:—Into the sleeves 4 two soap sticks 31 are inserted from above, the pressing piece 8 is pushed over the shaft 7, the spring 9 placed over said pressing piece, the lid 5 closed, the bobbin 29 with the paper roll 30 is inserted and the end of the strip of paper passed between the rolls 24. After the cash drawer 38 has been inserted from below and fixed by means of the locking rod 45, 46, the screw 47 being tightened, the cover plate 32 is put on and locked. If a coin of the required size, for instance a penny, is inserted into the coin-slot 50, of the coin-channel 51, it drops into the slots in the arms 13 and 20 where it is retained as it cannot pass through the small slot in the partition 48 above the coin-channel 40. In this manner the arm 13 is coupled with the arm 20 by the coin. If the arm 20 now is turned, the arm 13 is drawn along so that its pawl 14, which engages with the feed wheel 1, rotates this feed wheel and consequently the shaft 7 on which the knife 42 is fixed. In the beginning the knife 42 is in the position shown in Fig. 4 with respect to the soap blocks 31. If the handle-arm 20 and the elements coupled with the same are turned 180°, the knife 42 is moved along the lower end of one of the soap blocks 31 so that it cuts off a slice thereof. The coin-coupling, the arms 13 and 20 now having been brought over the wider slot 43 of the partition 48 drops through the same into the cash drawer 38, the arms 13 and 20 thus being uncoupled, so that, if the handle arm 20 is released, it returns to its initial position under the action of the spring 19. The arm 13 is pulled back also as a stud 52 of arm 20 engages with a notch 53 of arm 13, the pawl 14 coming out of engagement with the feed wheel 1. This feed wheel and the knife 42 do not participate in the back rotation, so that the knife 42 remains in such a position that, at the next operation of the arm 13, it will be moved along the second soap-block 31 and cut off a slice of the same.

Owing to the gearing of the toothed wheel 21 with the feed wheel 1, the rubber rolls 24 are rotated by the movement of the arms 13 and 20 through the intermediary of the gear

wheels 22^a and 22^b. The transmission of said gear wheels is selected so that these rubber rolls execute a complete rotation if the feed wheel makes only half a rotation. 5 In consequence of this arrangement strips of paper or fabric of always equal length are wound off the roll 30 and conveyed through between the rolls 24, said strip of paper or the like projecting through the 10 slot 49 so that it can be torn off from the outer side of the apparatus.

The cut off slice of soap drops through the center hole in the feed wheel 1 out of the apparatus, so that it can be removed or 15 caught by the hand hold underneath that spot.

If the coin inserted into slot 50 is not of the correct size it drops through the slots 20 of the arms 13 and 20 and the smaller slot 20 of the partition 48 into the coin-channel 40 and can be removed at the outer side of the apparatus.

At every half-rotation of the feed wheel 1 the pressing piece 8 which is brought into 25 engagement with the worm 17 of shaft 7 by the action of spring 9 is pushed down a corresponding distance so that it presses the soap sticks down unto the knife 42 in such a measure that the desired slice can be cut off 30 the soap sticks by the knife 42 when rotated. If the soap sticks have been consumed, the pressing piece 8 has disengaged from the thread 17 (Fig. 9) of shaft 7 and the spring 9' prevents the pressing piece 8 from bearing 35 onto the knife 42.

Several modifications also of the automatic device are possible without departing from the scope of invention. The arrangement may for instance be made in such a 40 manner, that the knife is stationary and the soap-blocks are rotatably arranged so that they will move along the knife. Instead of two soap-blocks only one soap-block of cylindrical shape may be used, only half a 45 slice being cut off at every operation.

Having now particularly described and ascertained the nature of my said invention, I declare that what I claim is:—

1. An apparatus for the simultaneous delivery of portions of soap and towel material comprising a container, a shaft arranged therein, a driving wheel secured to said shaft, a soap receptacle adapted to carry at 50 least one soap block arranged parallel to said shaft and above said wheel, a cutting knife secured to said shaft adjacent one end of said receptacle and adapted to cut a slice of soap from at least one of the soap blocks contained therein, a bobbin for carrying a 55 roll of towel material surrounding said shaft 60

and said soap receptacle, means for turning said bobbin connected to said driving wheel, and operating means connected to said driving wheel adapted to simultaneously rotate said cutting knife and said bobbin, whereby 65 a slice of soap and a portion of towel material may be delivered from said container.

2. An apparatus for the simultaneous delivery of portions of soap and towel material comprising a container, a shaft arranged longitudinally therein, a toothed driving wheel secured to said shaft, a soap receptacle 70 adapted to carry at least one soap block arranged parallel to said shaft above said wheel, a cutting knife secured to said shaft adjacent one end of said receptacle and adapted to cut a slice of soap from at least one of the soap blocks contained therein, a bobbin for carrying a roll of towel material surrounding said shaft and said soap receptacle and 75 extending parallel thereto, feed rollers adapted to engage the towel material carried by said bobbin, transmission gears connecting said feed rollers with said driving wheel, a movable arm carrying a pawl adapted to engage said toothed driving wheel, and an operating handle adapted to 80 selectively engage said movable arm to simultaneously rotate said cutting knife and said feed rollers, whereby a slice of soap and a portion of towel material may be delivered from said container.

3. An apparatus for the simultaneous delivery of portions of soap and towel material comprising a container, a shaft arranged 85 therein, a driving wheel secured to said shaft, a soap receptacle adapted to carry a plurality of soap blocks arranged in parallel around said shaft, a cutting knife secured to said shaft adjacent one end of said receptacle and adapted to cut a slice of soap from each of the soap blocks contained 90 therein, a rotatably mounted bobbin for carrying a roll of towel material surrounding said shaft and said receptacle, feed rollers adapted to engage the towel material carried by said bobbin and unroll a portion thereof, transmission gears connecting said feed rollers with said driving wheel, and an operating handle connected to said driving 95 wheel and adapted to rotate said cutting knife into conjunction with each of the soap blocks contained in said receptacle and simultaneously operate said feed rollers, whereby a slice of soap and a portion of 100 towel material may be delivered from said container.

In testimony whereof I have hereunto set my hand.

EDMUND WEIDNER.
